MIXING APPARATUS

Bernard Granville, White Plains, N. Y.

Application July 2, 1932, Serial No. 620,618

24 Claims. (Cl. 261—70)

My invention relates to apparatus employed for mixing liquids and gases, and more particularly to the type of mixer commonly referred to as a carburetor for use in supplying internal combustion engines with a fuel mixture of air and gasoline.

In the specification and drawings forming part of Letters Patent of the United States No. 1,612,632 issued to me December 28, 1926, is described and illustrated an apparatus of this character in which the proportion of air and liquid in the mixture is automatically determined by the rate of flow of air through the mixer, or in other words by the degree of suction due to the piston strokes or revolutions of the engine.

In the operation of internal combustion engines, it is desirable that the mixture of air and gasoline should have a definite ratio best suited to the characteristics of the engine, and that under varying operating conditions that ratio should remain constant in order to obtain high efficiency in fuel consumption. That is, assuming for instance, under given atmospheric conditions, gasoline quality and engine characteristics, a suitable mixture to be sixteen parts of air to one of gasoline for a given engine, then in order to operate that engine at the most efficient fuel consumption, that ratio should be maintained throughout under all operating conditions. It is well known that the flow of liquid increases at a greater rate under increased suction than does the flow of air. Therefore in a carburetor it is important to vary the feed of gasoline so that as the suction increases the feed of gasoline will increase in a gradually decreasing degree so that the predetermined ratio of air to gasoline will be maintained.

In the construction of carburetors one object is to provide for constant delivery to the engine of a mixture of air and gasoline of definite proportions. But, while the amount of gasoline drawn into the mixing chamber depends upon the air suction into or at the mixing chamber, and while the air suction varies with the engine speed, it does not follow that the amount of gasoline drawn into the mixing chamber will always give the right proportion under all operating conditions. Consequently it has been found that engines operate more or less under conditions in which the mixture is either too lean or too rich, or of constantly varying proportions, and hence at relatively low efficiency as to fuel consumption.

The object of the present invention is to provide an improved apparatus of the type disclosed in my patent above referred to, and whereby a

more efficient mixing of air and liquid fuel is obtained under all operating conditions of the engine. That is, a uniform mixture of proportions best suited to a given engine to secure maximum efficiency and minimum fuel consumption under all conditions and engine speeds, from idling to highest speed, and a more effective mixture for engine starting under all atmospheric conditions.

In carrying my invention into effect I employ the combination of Pitot tube and Venturi control for the mixing apparatus disclosed in my patent above referred to with certain new features in construction and mode of operation as herein-after described in connection with the accompanying drawings, in which

Figure 1 is a side elevation of the complete mixer; Figure 2 a top plan view; Figure 3 a detail vertical section on the line 3—3 of Figure 2; Figure 4 a detail horizontal section on the line 4—4 of Figure 1; Figure 5 a detail horizontal section on the line 5—5 of Figure 1; Figure 6 a vertical longitudinal section on the line 6—6 of Figure 2 showing the relative positions of the operating parts when the engine is at rest or idling; Figure 7 a similar view showing the position of the operating parts when the engine is running at high speed; Figure 8 a vertical longitudinal section of the air intake of the mixer showing the position and mounting of the Pitot tube and the means for adjusting its position; Figure 9 a detail vertical section of part of the main float chamber or reservoir taken on the line 9—9 of Figure 2 showing the valve for regulating the supply of liquid to the reservoir and its actuating float; Figure 10 a perspective and partial section of the mixer showing the air and liquid ducts connecting the several chambers; Figure 11 an enlarged vertical section showing the throttle and idling nozzles at the suction end of the mixer; Figure 12 an enlarged vertical section of the liquid nozzle in the venturi of the mixing chamber taken on the line 12—12 of Figure 6; Figure 13 an enlarged horizontal section on the line 13—13 of Figure 6; and Figure 14 a detail vertical section on the line 14—14 of Figure 13.

Referring to the drawings, and more particularly to Figures 1, 2, 6, and 7, it will be noted that the mixer is arranged into four sections or chambers, namely; air intake 1, liquid reservoir 2, spray supply chamber 3, and mixing chamber 4. As usual in mixers for internal combustion engines, the air intake has a throttle 5; the mixing chamber a throttle 6; and the liquid reservoir an adjustable supply connection 7, float 8 and valve 9. The walls of the mixer forming the

several chambers are cast in one piece, except that removable covers 10 and 11 are provided for reservoir 2 and supply chamber 3. Cover 10 has a boss 12 formed integral therewith and in which a duct 13 extends horizontally into the swivel joint of supply connection 7, and extending downward from duct 13 is a duct 14 into which is fitted a pin valve 9 as shown in Figures 6, 7, and 9. This valve opens by gravity 10 and the pressure of liquid thereon, and is actuated by float 8 to reduce or cut off the liquid supply to the reservoir as the float rises therein. Cover 10 is also fitted with an air vent for the reservoir as shown in Figures 2 and 3. This vent 15 is in the form of a screw plug 15 having a vent hole 16 and regulating screw 17. This vent insures free response of float 8 to the variation of liquid level in the reservoir, and a free flow of liquid from the reservoir through port 18 to the spray supply chamber. This port is located near the bottom of the reservoir and is controlled by hand adjusted pin valve 19, see Figure 4. This valve permits a predetermined flow of liquid to the spray supply chamber and permits adjustment 20 of the carburetor for engines having different normal fuel consumption ratings. Cover 11 is recessed and forms part of the spray supply chamber and supports part of the spray mechanism. This cover slopes downward to the side 25 nearest the reservoir and is provided with a drain port closed by a screw plug 20.

In the mixing chamber 4 is located a tubular member 21 having a tapering bore, as shown in Figures 6 and 7, to form a venturi with its throat 35 at the intake end of the mixing chamber. The Venturi tube 21 is preferably made in a separate piece instead of being formed as an integral part of the wall forming the mixing chamber, so that, if desired, the Venturi tube may 40 have a curve or taper adapted to the characteristics of the engine with which the carburetor is to be employed. The Venturi tube may be held in fixed position by a set screw 22, and while tube 21 might be arranged for adjustment relative 45 to the spray nozzle for effecting the initial adjustment of the mixer, I prefer to make the nozzle member adjustable by screwing it into port 23 and locking it in adjusted position by jam-nut 24. This method of obtaining the initial 50 adjustment of the nozzle relative to the throat of the venturi is preferable because it permits of finer adjustment and guards against unnecessary re-adjustments or tampering with this important adjustment after the mixer is once 55 properly set. As is well known, internal combustion engines have varying characteristics due to difference in proportions, construction, etc., and therefore the suction effect will vary, and consequently the same carburetor will not function 60 equally well with all engines. I have found that the curve or taper of a venturi in carburetors bears a definite relation to the characteristics of the engine in so far as the effect of suction is concerned; and that the taper of the liquid nozzle 65 and its adjustment within the throat of the venturi, and the ability to move the spray orifice of the liquid nozzle into areas of different air velocity within the venturi in synchronism with the engine speed are important factors in controlling the flow of liquid into the mixing chamber.

The spray mechanism which is shown in detail in Figures 6, 7, and 12, comprises the stationary adjustable nozzle member 25 which is screwed 75 into the port 23 in the lower wall of the air in-

take chamber; a reciprocating spray tube 26 sliding in a relatively long sleeve 27 rigidly mounted inside of nozzle 25, the tube 26 preferably having a flat top with a number of very small perforations as shown in Figure 5 for dividing the liquid into fine jets as it is drawn into the mixing chamber; a collar 28 secured to the inner end of spray tube 26; a link 29 pivoted to the collar; a lever 30 having its fulcrum at 31 within cover 11 and to which lever link 29 is connected at or near the middle; a cylindrical float 32 having a link connection 33 to the power end of lever 30; and a stationary air tube 34 projecting upward from an air port in cover 11, through lever 30 and link 29 and into the spray tube 26. Float 32 is located in a vertical cylindrical chamber 35, an extension of the supply chamber 3, and which chamber 35 is provided with four guide ribs 36 for guiding the float and to prevent the float tilting or binding against the wall of the chamber 20 and to permit liquid and air to circulate around the float. The air tube 34 is fitted through a screw threaded plug 37, as shown in Figure 12, and this plug is screwed through cover 11 from a small air chamber 38 formed in the projection 39, and which chamber is closed by a screw plug 40. Air enters chamber 38 through a screened air intake 41 and duct 42 which extends downward through ribs formed on the outside of the mixer body and cover 11 as shown in Figures 1, 10, and 12. This air passage is regulated by hand adjusted pin valve 43, see Figure 5. Float chamber 35 is provided with an air vent as shown in Figures 13 and 14. At the top of float chamber 35 is a vent plug 44 having a port and circumferential groove 45 registering with air passage 46, and which passage connects with ducts 47 and 48. Duct 46 is closed at the outer end by screw plug 46' (Figure 14) which may have a small vent hole bored through the plug to permit air to escape from or enter chamber 35, but I prefer to vent chamber 35 through duct 48 so that the vent will be well above the fluid level in chamber 35 when raised by air pressure from the Pitot tube as hereinafter explained. This vent 45 provides an air exhaust and intake for chamber 35, the exhaust preventing slowing or checking of the upward movements of the float due to air compression, and the intake preventing the slowing or checking of the downward movements 50 due to formation of a partial vacuum in the chamber, and thus insuring immediate and free response of float 32 to the change of liquid level in chamber 3 due to the variations of air pressure upon the liquid in the reservoir coming from the Pitot tube. Vent plug 44 is also provided with a bevelled edge forming a seat with which cone 49 at the top of float 32 contacts to shut off the escape of liquid through ducts 46 and 47 when float 32 reaches the limit of its upward movement.

The air supply entering intake 41 flows down through duct 42 and into chamber 38, and from that chamber flows upward through tube 34 to the spray tube 26 where the air mixes with the gasoline therein, and when the air suction through the venturi draws gasoline from tube 26, air is also drawn up through tube 34 and produces a pre-mixing which results in a much finer division and more rapid vaporization in the 70 mixing chamber 4 as the mixture from the spray tube encounters the main air supply drawn through the venturi. This primary mixing of air and gasoline within the spray tube must be so regulated that while producing a fine spray. 75

gasoline in sufficient volume will be drawn into the mixing chamber so that the proper proportion of air and gasoline is delivered to the engine, and it is for that purpose that regulating valve 43 is provided at the auxiliary air intake.

As shown in Figures 6, 7, and 12, the stationary nozzle member 25 is conical at the tip where the spray tube 26 projects therefrom and member 25 is so adjusted relative to the throat of venturi 21 that the conical tip and throat surface 21 will form a conical entrance for the air column entering from the intake chamber. The tip of spray tube 26 will thus be within the cone of the inrushing air when throttle 6 is opened and the suction will have the strongest effect to draw gasoline and air through the jet holes in a very fine spray or vapor which will be thoroughly mixed with the main air column as the air cone breaks into a solid column in the mixing chamber above the nozzle. By adjusting the air intake at the valve 43 while the engine is running, a mixture of the desired proportions may be obtained, and in the position of the spray tube 26 as shown in Figure 6 with the throttle open and the engine running at low speed, the selected proportion of air and gasoline will be maintained. As the engine speed increases, greater suction will result, and consequently a much greater proportion of gasoline will be drawn into the mixing chamber, resulting in a mixture richer in gasoline than the predetermined desired ratio, unless a balancing or retarding effect is introduced.

This balancing or retarding effect is obtained by the spray mechanism actuated by changes in air velocity through the intake 1 due to variations in engine speed. These changes in velocity vary the air pressure in the Pitot tube 50 located in the air intake chamber 1, see Figures 8 and 10, and this air pressure which is transmitted to the reservoir chamber acts upon the liquid therein to vary the liquid level in chamber 3, which in turn causes float 32 to actuate the spray mechanism. The leverage between float 32 and spray tube 26 provides a two to one movement, so that the rise and fall of the float is translated into corresponding movements of the spray tube of one-half the distance, thus providing a very fine automatic readjustment of the tip of spray tube 26 within the venturi, and whereby the tip is moved progressively out of, or into, areas of different air velocity, synchronously with the rise and fall of the R. P. M. of the engine. Under the assumed condition of Figure 6, and the throttle 6 open, it will be seen that as the engine speeds up and the air velocity through the venturi increases, the tendency would be to disproportionately increase the quantity of gasoline drawn into the mixing chamber, but that this tendency is retarded by the action of the spray mechanism, as actuated by the air pressure from the Pitot tube, to gradually move the tip of the spray tube out of the point of greatest suction thereby reducing the effect of the suction at the spray tube, and while an increased quantity of gasoline would be drawn into the mixing chamber as the air velocity increased, the rate at which gasoline is drawn from the spray tube would be reduced, thus maintaining the desired ratio of air to gasoline.

As shown in Figure 8, Pitot tube 50 projects at an angle through the wall of the air intake chamber 1, to the center of that chamber, and the inlet end of this tube is bent as shown at 51 so that the axis of the bent end will lie directly in and parallel with the center of the air column

entering chamber 1. This tube is perforated or has its wall cut away about one-half as shown at 52 so as to register with an air duct 53 formed in a rib 54, see Figure 1. This duct extends to a point within shoulder 55 on the reservoir wall 5 where it enters a hole 56 drilled vertically into shoulder 55. On the cover 10 are two projections 57 which are drilled through to receive a bent tube 58, one end of which projects through the cover for insertion into hole 56 and the other end opening into the reservoir to complete the air passage from the Pitot tube 50 by way of duct 53 and tube 58 to the reservoir. The purpose in having this air passage enter the reservoir chamber by way of bent tube 58, instead of entering directly through shoulder 55, is to prevent gasoline over-flowing through passage 53 into the air intake chamber 1. Pitot tube 50 is mounted in the bore of an adjusting knob 59 (Figures 1 and 8) and secured against turning therein by pin 20 60. Knob 59 has a screw-threaded shank 61 which is threaded into a socket in boss 62, and the periphery of the knob is milled or notched for engagement by a spring detent 63 to hold the knob in its adjusted position. Air duct 53 is 25 closed at the outer end by a screw plug 64 which may be removed for cleaning the air passage. The purpose in threading the shank of the knob into the socket is to permit turning the tube 50 for adjusting the position of tip 51 in the air 30 column and at the same time prevent longitudinal movement of the tube after adjustment. This could be done without a screw-thread, but a thread requires no extra parts, and since a very fine thread may be provided, the longitudinal 35 movement thus imparted to the tube in adjusting tip 51 will be negligible, because, to obtain the maximum adjustment of tip 51, the rotation of the tube and knob will never exceed a quarter turn. The purpose in changing the position of tip 51 in the air column is to take advantage of the gradual decrease of velocity in the air column from the center toward the circumference, and thus vary the pressure of the air forced through tube 50 into the reservoir.

In Figures 6 and 7 the spray mechanism is shown in extreme opposite positions, the former showing the throttle 6 closed and therefore no suction through the air intake 1, and the latter showing the throttle wide open to permit the maximum suction. When the suction is reduced or cut off as in Figure 6, there is decreased or no air pressure through Pitot tube 50 and consequently the liquid level in chambers 2 and 3 will be unaffected by air pressure and stand at the normal level in both chambers. Under this condition float 32 and connected spray mechanism will be at the lowermost position as shown in Figure 6 with the spray tube 26 in position to deliver, when the throttle is opened, the quantity of gasoline required for the predetermined mixture. In Figure 7 the throttle is wide open and the spray mechanism in the position of high air pressure indicating that the suction is very strong due to high engine speed. In this position the spray tube 26 is elevated to its extreme limit within the venturi, where it is least affected by the suction because of its distance from the throat and because of the increased cross sectional area of the venturi at that point, and consequently the ratio of gasoline emission to air velocity is reduced, but without reducing the predetermined ratio of air to gasoline. If, while the engine is running at high speed, it should be found that the mixture is rich or lean, gasoline

valve 19 and air valve 43 should be tested and adjusted if necessary. But, if after testing or adjusting for too lean a mixture, for instance, it is found that the mixture is still lean, slowness of gasoline emission at the spray tube would be indicated. This condition may then be remedied by adjusting the tip 51 of the Pitot tube out of the stream center, step by step, by turning knob 59, thereby reducing the air pressure 5 in the reservoir, and allowing the spray tube to descend to a point or area in the venturi where the air suction will draw the desired amount of gasoline. The adjustment of tip 51 of the Pitot tube from the center to the outer circumference 10 of the air column will afford a very wide range 15 of adjustment for increasing or decreasing the gasoline emission at the spray tube.

The air and liquid supply for the engine while idling, as well as the starting supply, enter the 20 upper part of the mixing chamber through two small nozzles or ports adjacent the throttle valve 6 as shown in Figures 11 and 13. One of these ports delivers a minute mixture for the primary 25 or normal idling speed of the engine, and the other port delivers a larger quantity as the secondary speed mixture before the main spray nozzle 26 starts to function. These small ports might be located apart from each other, but both 30 adjacent the throttle, but I prefer to arrange them as a single unit drawing liquid from reservoir 2 or supply chamber 3 through the same duct. With this object in view I provide a hole 35 in the wall of the mixing chamber 4 in which is fitted a plug 66 having its inner face concaved to match the bore of chamber 4, and this plug is provided with two small mixing chambers 67 and 68 formed therein, preferably in vertical alignment, and which chambers have very small discharge orifices 69 and 70, respectively, the 40 former about one-half the size of the latter. The bore of each chamber 67 and 68 is enlarged and screw-threaded to receive air nozzles 71 and 72, each having an air intake port 73 drilled through the heads of the nozzles and in each 45 head is a valve screw 74 for regulating the air intake. Plug 66 has a port 75 drilled laterally to the center of the plug where it cuts into the enlarged bore of each chamber 67 and 68 between the two nozzles as best seen in Figure 11. 50 When plug 66 is in position, its port 75 registers with port 76 (see Figure 13) drilled horizontally in the body wall, and this port connects with duct 77 extending vertically down through the body wall and opening into liquid chamber 3 as 55 shown in Figures 1 and 10. A flat spring 78 is secured on throttle valve 6, and bent over the edge of the valve which is notched to permit the spring blade to pass between it and plug 66 without binding. This blade is provided for the purpose of covering the orifice 70 when the throttle 60 is in its closed position as shown in Figure 6 so that only nozzle 69 will function; that is nozzle 67-71 will deliver the primary gasoline and air mixture when the engine is operating at low 65 idling speed. When increased or higher idling speed is desired, the throttle is opened slightly, thus removing blade 78 from nozzle 70 and permitting delivery of the additional secondary mixture for increasing the speed of the engine. Under 70 these circumstances the action of the mixer will be as follows: With the throttle 6 closed as in Figure 6, and the engine idling, there will be insufficient suction to draw air and liquid into the mixing chamber 4 through the main spray nozzle 26, but what suction there is above the throt-

tle will be sufficient to draw air through nozzle 71 whose orifice 69 is open as seen in Figure 11, and this suction will draw liquid up through duct 77, ports 76 and 75, and into chamber 67, and the mixing of air and liquid in that chamber will cause a vaporous mixture to be drawn through orifice 69 into the channel above the throttle 6 and into the engine cylinders, delivering sufficient fuel to maintain the engine at its idling speed. For increased speed the throttle 6 is opened 10 slightly, only far enough to uncover orifice 70 (but not enough to create a sufficient suction to operate the main spray nozzle) and now with both orifices 69 and 70 open a much greater vaporous mixture will be drawn into the channel 15 above the throttle and into the engine cylinders. The desired proportion of air and gasoline for the idling nozzles is obtained by adjusting nozzles 71 and 72 to regulate the flow through orifices 69 and 70 from chambers 67 and 68, and the 20 air supply is regulated by adjusting screws 74 to control the air intake through ports 73.

Throttles 5 and 6 are mounted in the usual manner on spindles having the usual actuating levers and adjustable stops, but since these details are not new and well understood detailed description and reference numerals on the drawings are omitted.

The operation of my improved carburetor will be understood from the foregoing description of 30 the structural features and their functioning, but in order to call attention to an additional function of the Pitot tube the following explanation is made. In Figure 6, the throttle 6 is closed and consequently the secondary or intermediate nozzle 35 orifice 70 is also closed, and therefore, the carburetor is in the inoperative condition with the engine not running at all, and ready for starting, or in an operative condition with the engine running at low idling speed with fuel mixture being 40 delivered only from nozzle orifice 69. At such times the normal liquid level in chambers 2 and 3 would be below the tops of floats 8 and 32, and in the nozzle 25-26 considerably below the top or orifice of air tube 34, leaving an air gap within 45 the upper part of spray tube 26 through which the liquid must pass as it is drawn into the mixing chamber 4. This space in the spray tube therefore constitutes an auxiliary mixing chamber. When throttle 6 is opened slightly, nozzle orifice 50 70 is also opened, permitting additional fuel mixture to be drawn into the suction pipe and cause the engine to speed up. Suction now increases through intake 1 and begins to draw air and gasoline from spray nozzle 26 and thus the fuel feed 55 is brought up, step-by-step, preventing the consequences of too sudden a jump from starting or low idling fuel feed to a relatively high speed fuel feed. With this increased suction the tendency is to draw into the mixing chamber a mixture of 60 greater gasoline value than the selected ratio, but the Pitot tube now begins to function and the liquid in chamber 2 is subjected to air pressure which will increase as the engine speed increases. This pressure raises the liquid level in chamber 3 65 and consequently float 32 rises and carries spray tube 26 upward, but to a lesser degree owing to the leverage. This upward movement of spray tube 26 carries the spray orifices into areas of 70 decreasing air velocity in the venturi, and while the increasing suction draws larger quantities of fuel mixture, the movement of the spray tube orifices into areas of less velocity will overcome the tendency of the increased suction to dispro- 75

portionately increase the amount of liquid drawn into the mixing chamber and thereby preserve the selected ratio of air and liquid. It will be observed that, as the spray tube 26 rises in the venturi, while the air tube 34 remains stationary, the air gap within the tube 26 remains practically constant, or is slightly reduced, owing to the rise of liquid due to the air pressure from the Pitot tube, that is, the liquid rises with the elevation 5 of the spray tube, and therefore, the elevation of the spray tube does not affect the pull required to draw the liquid into the mixing chamber. With the increase in air pressure in the liquid chamber as the engine speeds up, the liquid in chamber 3 would rise and be forced out of the spray tube 26 and also be forced into vent 44 in chamber 35, if the pressure were not relieved and regulated. It is for this purpose that regulating vent 15 (Figure 3) is provided. By this means 10 the air pressure may be regulated in chamber 2 so that the Pitot tube will function both as the means for controlling the adjustment of the spray nozzle as the engine speed varies as well as assisting in the feed of gasoline to the mixing chamber 15 and facilitating the mixing of air and gasoline in the auxiliary mixing chamber of the spray tube.

What I claim is:

1. In apparatus of the class herein described, the combination with a mixing chamber, air intake and liquid chamber, of a nozzle comprising a stationary member communicating with the liquid chamber and having a fixed position at and limiting the area of the entrance to the mixing chamber and a reciprocating tube within said member, and mechanism controlled by the velocity of the air through said intake for reciprocating said tube within the mixing chamber in synchronism with the variations in engine suction, and thereby automatically reducing the rate 20 of liquid emission from said tube relative to the air intake as the engine suction increases, and vice versa.

2. In apparatus of the class herein described, the combination with an air intake, liquid chamber, and mixing chamber tapering to form a throat 25 between said chamber and air intake, of a nozzle comprising a stationary member having a set position at and limiting the area of said throat and communicating with the liquid chamber and a reciprocating spray tube, mechanism for reciprocating said spray tube to move its orifice vertically in the mixing chamber to vary the suction effect thereat and thereby automatically reducing the rate of liquid emission from the spray 30 tube relative to the air intake as the engine suction increases, and vice versa, and means for applying air pressure from the intake chamber to actuate said mechanism in synchronism with the engine speed.

3. In apparatus of the class herein described, the combination with a mixing chamber, air intake and liquid chamber, of a stationary nozzle 35 communicating with the liquid chamber and having a fixed position at and limiting the area of the entrance to the mixing chamber, a spray tube within said nozzle adapted to move axially within said nozzle and project into the mixing chamber, a Pitot tube located in the air intake, and mechanism actuated through the air pressure from the Pitot tube for reciprocating said spray tube as the air velocity varies in the intake.

4. In apparatus of the class herein described, the combination with a mixing chamber, air intake and liquid communicating with the liquid 40 chamber and, of a stationary nozzle member pro-

jecting into the mixing chamber, a reciprocating spray tube within said nozzle, a Pitot tube located in the air intake, mechanism actuated through the air pressure from the Pitot tube for reciprocating said spray tube as the air velocity varies in the intake, and means for adjusting the position of the impact orifice of the Pitot tube in the air column.

5. In apparatus of the class herein described, the combination with a mixing chamber, air intake and liquid communicating with the liquid chamber and, of a stationary nozzle member projecting into the mixing chamber, a spray tube within said nozzle adapted to move axially within said nozzle and project into the mixing chamber 10 a lever for moving said tube, and means responding to the air velocity through the intake for controlling the movements of said lever.

6. In apparatus of the class herein described, the combination with a mixing chamber, air intake and liquid chamber, of a stationary nozzle communicating with the liquid chamber and projecting into the mixing chamber, a reciprocating spray tube within said nozzle, a lever for moving said tube, a float connected with said lever and responding to changes in liquid level in the liquid chamber, and an air duct from the intake to the liquid chamber for subjecting the liquid to air pressure and cause the float and lever to respond to variations in air velocity through the intake.

7. In apparatus of the class herein described, the combination with an air intake, liquid chamber, and mixing chamber tapering to form a throat between said chamber and air intake, of a stationary nozzle member having a tapering end adjustably set at and limiting the area of said throat, a reciprocating spray tube within the nozzle member, and mechanism responding to variations in air velocity through the intake for moving the spray tube orifice into areas of different air velocity in the mixing chamber to vary the suction effect at the spray orifice, and thereby automatically reducing the rate of liquid emission from the spray tube relative to the air intake as the engine suction increases, and vice versa.

8. In apparatus of the class herein described, the combination with an air intake, liquid chamber, and mixing chamber tapering to form a throat between said chamber and air intake, of a stationary nozzle member communicating with the liquid chamber and having a tapering end and adjustable relative to said throat, a spray tube within the nozzle member, mechanism for reciprocating said tube, and a Pitot tube located in the air intake and communicating with a chamber wherein the air pressure from said tube acts upon said mechanism to cause same to respond to variations in air velocity through the intake for moving the spray tube orifice into areas of different air velocity in the mixing chamber to vary the suction effect at the spray orifice.

9. In apparatus of the class herein described, the combination with an air intake, liquid chamber, and mixing chamber tapering to form a throat between said chamber and air intake, of a stationary nozzle member having a tapering end and adjustable relative to said throat, a reciprocating spray tube within the nozzle member, a float actuated lever connected with the spray tube and responding to changes in liquid level in the liquid chamber, a Pitot tube in the air intake, and an air duct from said tube to the liquid chamber for subjecting the liquid to air pressure and cause said float actuated lever to move the orifice of the spray tube into areas of different air velocity in

the mixing chamber in synchronism with variations in air velocity through the intake.

10. In apparatus of the class herein described, the combination with a mixing chamber, air intake and liquid chamber, of a spray nozzle comprising a stationary member having a fixed position at and limiting the area of the entrance to the mixing chamber and a reciprocating spray tube projecting into the mixing chamber, mechanism controlled through the engine suction for moving the spray orifice of said tube into areas of different air velocity in the mixing chamber, and an auxiliary adjustable air intake for admitting air into the spray tube for mixture with the liquid therein, whereby a mixture of air and liquid of selected proportions is drawn into the mixing chamber for mixture with the air entering said chamber from the main air intake at a rate varying with the variations in engine suction.
15. In apparatus of the class herein described, the combination with a mixing chamber, air intake and liquid chamber, of a spray nozzle comprising a fixed member communicating with the liquid chamber and a reciprocating spray tube projecting into the mixing chamber, a float mechanism responding to variations in engine suction for moving the spray orifice of said tube into areas of different air velocity in the mixing chamber, and an auxiliary air intake comprising an air tube 20 projecting inside the spray tube, an air duct leading from the exterior to said air tube and an adjustable valve for regulating the flow of air into said spray tube, whereby a selected mixture of air and liquid is drawn into the mixing chamber and 25 mixed with the air entering said chamber from the main air intake at a rate varying with the variations in engine suction.

30. 12. In a carbureter, the combination with the air intake, liquid chamber, and mixing chamber, of a venturi between the intake and mixing chamber, a liquid nozzle comprising a stationary member and a spray tube projecting therefrom and movable vertically in the venturi, an auxiliary air intake, a valve for regulating said intake to provide a selected ratio of air and liquid, a float controlled lever connected with said spray tube; and a Pitot tube located in the air intake and communicating with the liquid chamber, whereby the pressure created by the engine suction is caused 35 to actuate said lever and reciprocate said spray tube in synchronism with the engine speed to automatically move the spray orifice into areas of different air velocity to vary the rate of emission therefrom and automatically maintain the selected ratio of air and liquid.

40. 13. In a carbureter, the combination with a mixing chamber, air intake and liquid chamber, of a spray nozzle having a movable element, float actuated mechanism for moving said element, an auxiliary liquid chamber in which the float is confined, means for subjecting the liquid to air pressure to cause the float mechanism to move said spray element in synchronism with the changes in engine speed, and air vents for said liquid chambers.

45. 14. In a carbureter, the combination with a mixing chamber, air intake and liquid chamber, of a spray nozzle having a movable element, float actuated mechanism for moving said element, an auxiliary liquid chamber in which the float is confined, means for subjecting the liquid to air pressure to cause the float mechanism to move said spray element in synchronism with the changes in engine speed, and an adjustable air 50 vent at the top of said auxiliary liquid chamber.

5. 15. In a carbureter, the combination with a mixing chamber, air intake and liquid chamber, of a spray nozzle having a movable element, a float actuated mechanism for moving said element, an auxiliary liquid chamber in which the float is confined, means for subjecting the liquid to air pressure to cause the float mechanism to move said spray element in synchronism with the changes in engine speed, an adjustable air vent for the main liquid chamber, an air vent at the top of said auxiliary liquid chamber, and a valve member for the latter vent controlled by the float.

10. 16. In a carbureter, the combination with the air intake, liquid chamber, and mixing chamber, of a venturi between the intake and mixing chamber, a stationary nozzle member projecting into and adjustable axially within the throat of said venturi, a movable nozzle member projecting from said stationary member and movable axially within said venturi, and mechanism controlled by the air velocity through the intake for reciprocating said movable nozzle member.

15. 17. In a carbureter, the combination with the air intake, liquid chamber, and mixing chamber, of a venturi between the intake and mixing chamber, a stationary nozzle member projecting into and adjustable axially within the throat of said venturi, a sleeve mounted in said nozzle member, a tubular spray member sliding in said sleeve and movable axially within the venturi, and mechanism controlled by the air velocity through the intake for reciprocating said movable nozzle member.

20. 18. In a carbureter, the combination with the air intake, liquid chamber, and mixing chamber, of a venturi between the intake and mixing chamber, a liquid nozzle having a member movable axially within the venturi, mechanism actuated by air pressure for moving said member, a Pitot tube in the air intake, and an air duct communicating with said tube for supplying the air pressure for actuating said mechanism for reciprocating the movable nozzle member in synchronism with the engine speed.

25. 19. In a carbureter, the combination with the air intake, liquid chamber and mixing chamber, of a venturi between the intake and mixing chamber, a liquid nozzle having a member movable axially within the venturi, means actuated by air pressure for moving said member, a Pitot tube projecting into said air intake and having a bent impact end normally parallel with and in the center of the air column, and means for rotating said tube to adjust the impact end of said tube to varying velocities to vary the effect on said movable nozzle member.

30. 20. In a carbureter, the combination with the air intake, liquid chamber and mixing chamber, of an auxiliary mixing chamber for furnishing the fuel mixture for idling speed, a liquid duct leading thereto from the liquid chamber, an outlet orifice from the auxiliary mixing chamber opening into the suction pipe above the throttle, an air nozzle having a bevelled tip adapted to cooperate with a bevelled entrance to the auxiliary mixing chamber to form a valve for the control of fluid thereto, and a valve screw in said nozzle for regulating the flow of air through the nozzle.

35. 21. In a carbureter, the combination with the air intake, liquid chamber and mixing chamber, of a pair of auxiliary mixing chambers for furnishing a primary and a secondary fuel mixture for low and intermediate speeds, a liquid duct leading thereto from the liquid chamber, an air 40

inlet for each auxiliary chamber, an outlet orifice from each of said auxiliary mixing chambers opening into the suction pipe at the throttle, and a spring blade mounted on the throttle for covering the secondary mixture orifice when the throttle is closed.

5 22. In a carbureter, the combination with the air intake, liquid chamber and mixing chamber, of a pair of auxiliary mixing chambers for furnishing a primary and a secondary fuel mixture for low and intermediate speeds, a liquid duct leading thereto from the liquid chamber, an air nozzle for each auxiliary mixing chamber and adapted to control the flow of both liquid and air 10 to said chambers, an outlet orifice from each of said auxiliary mixing chambers opening into the suction pipe at the throttle, and a closure for the secondary mixture orifice adapted to be moved into closed position when the throttle is closed.

15 23. In a carbureter, the combination with the air intake, liquid supply chamber and mixing chamber, of an auxiliary mixing unit comprising a block fitted in the wall of the suction end of the mixing chamber at the throttle, and having 20 two small mixing chambers formed therein and having outlet orifices therefrom in vertical alignment, an air nozzle for each of said chambers and each nozzle having means for controlling the flow 25

of air, and said nozzles being individually adjustable in said block to regulate the flow of liquid to the mixing chambers, and a liquid duct in said block communicating with the entrances to both said chambers and adapted to register with a duct leading to the liquid supply chamber. 5

24. In a carbureter, the combination with the air intake, liquid chamber, and mixing chamber, of a nozzle projecting into the mixing chamber 10 and communicating with the liquid chamber and comprising a stationary and a movable element, an air tube projecting into the nozzle, an auxiliary air intake leading to said air tube to effect a mixing of air and liquid within said nozzle, a 15 float actuated mechanism for reciprocating said movable nozzle element, a Pitot tube in the main air intake, and an air duct leading from the Pitot tube to the liquid chamber for subjecting the liquid to pressure, whereby the pressure will 20 cause the float mechanism to reciprocate the movable nozzle element in synchronism with the engine speed, and the mixture of air and liquid in the nozzle will be acted upon both by suction and pressure in effecting its emission into the 25 mixing chamber for mixture with the air from the main intake.

BERNARD GRANVILLE.
